SIGNAL PROCESSING ARRANGEMENT

John P. Costas, Fayetteville, N. Y., assignor to General Electric Company, a corporation of New York
Application March 15, 1957, Serial No. 646,430

10 Claims. (Cl. 250—36)

My invention relates to signal processing arrangements and particularly to methods and means for providing a large number of signals of high frequency stability.

Prior art methods and means have made use of a crystal controlled oscillator for providing a signal of high frequency stability. Where large numbers of such signals are required, the prior art arrangements have proven to be overly complicated and expensive to construct.

It is therefore an object of my invention to provide an improved signal processing method and arrangement.

Another object of my invention is to provide a large number of signals of high frequency stability with a minimum of circuitry.

Another object of my invention is to provide an improved phase control arrangement.

Another object of my invention is to provide an improved phase discriminator.

Another object of my invention is to provide an improved method and means for deriving a large number of discrete frequencies of high frequency stability from a single stable reference frequency source.

It is a further object of my invention to provide a continuously tunable source of signals of high frequency stability and accuracy.

In accordance with one embodiment of my invention, means are provided for deriving, from a single stable reference frequency source, at least two signals of different frequency f_a and f_c , such as may be derivable from a harmonic series having a fundamental frequency as the reference frequency, generating a signal having a frequency f_b intermediate f_a and f_c , comparing the signals corresponding to f_a , f_b and f_c to derive a control signal, and using the control signal to maintain the frequency f_b at a predetermined frequency with respect to the signals f_a and f_c .

The novel features which are believed to be characteristic of this invention are set forth with particularity in the appended claims. The invention, itself, however, both as to its organization and method of operation, together with further objects and advantages thereof, may best be understood when taken in connection with the accompanying drawings in which—

Fig. 1 is a block diagram of one embodiment of my invention, Figs. 2a and 2b, 3a, 3b and 5 illustrate graphically certain waveforms useful in explaining the operation of the present invention, and Fig. 4 illustrates in block diagram form a further embodiment of the present invention.

Referring to Fig. 1, there is shown a method and means for obtaining signals of many different frequencies of crystal stability while employing a tunable oscillator in conjunction with an oscillator having a single crystal control. It is desired to provide over lead 1, for application to an output circuit 2, signals of a frequency stability comparable to that available at the output of the crystal oscillator or reference signal source 3 but of different frequencies. In accordance with one embodiment of the invention, two signals of different fre-

quency are derived from a reference signal source in such a manner as to substantially maintain the frequency stability of the reference signal. In accordance with one embodiment, source 3 supplies a reference signal of substantially constant amplitude to a harmonic generator

4. Harmonic generator 4 operates in response to the supplied reference signal to deliver at its output lead 5, a plurality of harmonically related signals, as for example, of frequency f_a and f_c shown in Fig. 2a. In Fig. 2a, frequency is plotted as abscissa and signal occurrence is plotted as ordinate. The frequency spacing between the frequencies f_a and f_b and between f_b and f_c is shown to be equal.

Oscillator 6 provides signals at its output lead 7 within a frequency range corresponding to that desired at the output circuit 2. The oscillator signals available from the source 6 and the harmonically generated signals available from source 4 are mixed in mixer circuit 8 to provide at the output lead 9 a low frequency signal whose amplitude varies in accordance with the relative phases of the signals available over leads 5 and 7. The mixer circuit 8 may comprise any of the well-known circuits which beat together or multiply input signals to provide a resultant output signal. The specific characteristics

20 of the signals available over lead 9 and how they are employed to control the operation of oscillator 6 will be described in detail later. For purposes of our discussion, assuming the frequency, f_b , of the oscillator 6 was selected to be half-way between that of the signals f_a and f_c as shown in Fig. 2a, the signals available over lead 9 would have a beat frequency f_r . These signals, upon being amplified to a suitable level in amplifier 10, are detected or converted to a direct signal by the amplitude detector 11 and applied over lead 12 to a frequency control circuit 13. Frequency control circuit 13 operates to adjust the frequency of oscillator 6 in a desired direction. The frequency control circuit 13 may comprise one of the many well-known varieties available in the art, and in particular may comprise a reactance 25 tube type frequency control circuit.

As previously mentioned, the mixer circuit 8 has supplied to it a plurality of harmonically related signals, as shown in Fig. 2a, which have been derived from the crystal controlled oscillator 3. The frequency of oscillator 6 was selected to be somewhere near the midpoint between the crystal controlled frequencies f_a and f_c . Under these circumstances the mixer provided at its output a resultant signal of frequency f_r (equal to

50

$$\frac{f_c - f_a}{2}$$

derived from the products $f_b - f_a$ and $f_c - f_b$) whose amplitude varied as the phase of the signal available from oscillator 6 varies with respect to the phase of the signals f_a and f_c . This may be represented mathematically as follows. Fig. 2a represents a pair of harmonics with frequencies f_a and f_c . The tunable oscillator frequency f_b is shown at a point midway between f_a and f_c . Let the 55 two harmonic signals be represented by $h_a(t)$ and $h_c(t)$, and the tunable oscillator signal by $h_b(t)$. Then

$$h_a(t) = \cos(2\pi f_a t + \phi_a) \quad (1)$$

$$h_b(t) = \cos(2\pi f_b t + \phi_b) \quad (2)$$

and

$$h_c(t) = \cos(2\pi f_c t + \phi_c) \quad (3)$$

where t is time and ϕ_a , ϕ_b and ϕ_c are the fixed phase angles of the three signals. The output of mixer 8 will then be given as

$$m(t) = [h_b(t) + h_c(t)] \times h_a(t) \quad (4)$$

which results in

$$m(t) = \frac{1}{2} \cos [(w_b - w_a)t + \phi_b - \phi_a] + \frac{1}{2} \cos [(w_c - w_b)t + \phi_c - \phi_b] \quad (5)$$

when difference frequency terms only are considered and where $w_a = 2\pi f_a$, $w_b = 2\pi f_d$ and $w_c = 2\pi f_c$. Now, if the frequency of oscillator 6 lies exactly midway between w_c and w_a

$$w_b - w_a = w_c - w_b = \Delta w \quad (6)$$

where Δw represents one half the frequency difference between harmonics $h_a(t)$ and $h_c(t)$. Equation 5 may then be rewritten as

$$m(t) = \frac{1}{2} \cos [\Delta w t + \phi_b - \phi_a] + \frac{1}{2} \cos [\Delta w t + \phi_c - \phi_b] \quad (7)$$

Manipulating Equation 7 by use of trigonometric identities yields

$$m(t) = \cos \left[\frac{\phi_b - \phi_c + \phi_a}{2} \right] \times \cos \left[\Delta w t + \frac{(\phi_c - \phi_a)}{2} \right] \quad (8)$$

Equation 8 is the output of mixer 8 referred to above with an amplitude which varies as the phase of the signal available from oscillator 6 but with a phase which is independent of tunable oscillator 6 phase ϕ_b . Upon amplification and amplitude detection of this resultant signal, there is provided at lead 12 a direct control signal whose amplitude varies, depending upon the phase of oscillator 6, in accordance with the characteristic shown in Fig. 2b. If the reactance circuit 13 is adjusted to operate on the XAZ portion of the characteristic curve of Fig. 2b, and in particular about the dotted reference line O, desired phase control of oscillator 6 can be achieved. For example, if the phase of oscillator 6 should increase in the direction A to Z, a control signal is generated by the reactance tube which returns the phase of oscillator 6 to its desired level. On the other hand, if the phase of oscillator 6 should decrease in the direction A to X, reactance tube provides an appropriate control signal which adjusts the phase of oscillator 6 back to its desired level. Thus the arrangement disclosed will operate to maintain the frequency of oscillator 6 midway between the frequencies f_a and f_c . Since the frequencies f_a and f_c were derived from the crystal control oscillator 3, their stability corresponds to the stability of the crystal controlled oscillator. Correspondingly, the frequency of the oscillator 6 will be regulated to a comparable stability.

While I have described the frequency f_b as having been selected to occur somewhere between the midpoint of the most adjacent harmonically related signals f_a and f_c , it is obvious that the invention can be practised in the case where the frequency f_b is made to occur somewhere near the midpoint of other pairs of sidebands, as for example as shown in Figs. 3a and 3b where frequency is plotted as ordinate and signal occurrence is plotted as abscissa. In Fig. 3a, the frequency f_b may be compared with the most adjacent sidebands $(N+1)f_0$ and $(N+2)f_0$ where N is any integer and f_0 is the crystal reference frequency, or with other sideband pairs such as Nf_0 and $(N+3)f_0$. Similarly, the f_b can be selected to coincide with one of the harmonics, as for example $(N+3)f_0$ shown in Fig. 3b. Again the frequency f_b in this latter case can then be compared with the most adjacent harmonics or further removed harmonics, as for example $(N+1)f_0$ and $(N+5)f_0$.

The present invention may also be employed to provide a continuously variable signal of high frequency stability and accuracy. Referring to Fig. 4, a portion of the circuit labeled L may be identical to that of Fig. 1 previously described and accordingly the common reference numerals have been retained in Fig. 4. Thus at the output lead 1 there is provided any one of a large

number of signals of discrete frequency having a stability comparable to that of the crystal oscillator circuit 3. The second portion of the circuit of Fig. 4, labeled M, is adapted to utilize the signal available over lead 1 in order to provide at the output lead 15 a continuously variable frequency signal having a frequency stability comparable to that of the crystal oscillator 3. The circuit may also be adapted to provide one of a large number of signals of discrete frequency having a frequency stability comparable to that of the oscillator 3 but occurring in frequency intervals which are smaller than the signals available over lead 1 from circuit L. These signals may then be applied to an output circuit 16 for desired utilization. To accomplish these desired results, the oscillator 17 is selected to have a frequency corresponding to that of f_d shown in Fig. 5a. In Fig. 5 frequency is plotted as ordinate and signal occurrence is plotted as abscissa. In order to maintain the frequency of oscillator 17 at the desired frequency level, the signal of frequency f_d is mixed with the signal f_b available over lead 1 and the beat signal or difference between these two is applied over lead 19 to a phase detector 20. The phase detector is also supplied with a signal f_e available from the oscillator 21 over lead 22. Referring to Fig. 5 again, it is noted that the frequency f_e has a predetermined relationship with respect to that of the signals f_b and f_d , namely the difference frequency therebetween. It is obvious that f_d can be either above or below f_e . The resultant output of the phase detector 20 is a direct signal whose amplitude and polarity is representative of the difference in phase between the signals available on lead 19 from the mixer 18 and the signal available on lead 22 from the oscillator 21. The resultant or control signal is applied to a frequency control circuit 23 over lead 23a which in turn adjusts the frequency of oscillator 17 in the proper direction to maintain its frequency at the desired frequency level f_d . As previously explained, the frequency control circuit 23 may comprise a reactance tube type control circuit. The result is that at output lead 15 there is provided signals of frequency f_d which have very nearly the stability of the crystal oscillator 3 but which may be continuously varied in frequency in accordance with the frequency selected and made available by oscillator 21.

If the switch 24 is moved to position 25, the oscillator 21 is replaced with the discretely tuned oscillator 26 which delivers at its output lead any one of a number of discrete frequencies. In a preferred embodiment the oscillator 26 comprises a circuit arrangement similar to that shown in Fig. 1 and corresponding to the circuit portion L of Fig. 4. The steps of frequency available from source 26, of course, are made to be finer than that available on lead 1 from the circuit portion L of Fig. 4.

While a specific embodiment has been shown and described, it will of course be understood that various modifications may yet be devised by those skilled in the art which will embody the principles of the invention and be found in the true spirit and scope thereof.

What I claim and desire to secure by Letters Patent of the United States is:

1. In combination, a source of a signal of highly stabilized frequency f , means responsive to said f frequency signal for providing at least two signals f_a and f_c of substantially the same high stability but of different frequency, a controllable source of a signal of frequency f_b , means for multiplying said signals of frequency f_a and f_c with said signal of frequency f_b to derive a resultant signal of frequency dependent upon the multiplication products $f_b - f_a$ and $f_c - f_b$, means for amplitude detecting said resultant signal, and means responsive to said amplitude detected resultant signal for controlling the frequency f_b of said signal from said controllable oscillator to be

$$\frac{f_a + f_c}{2}$$

2. In combination, a source of a signal of highly stabilized frequency f , means for providing at least two harmonically related signals f_a and f_c in response to said f frequency signal, a controllable source of a signal of frequency f_b , means for mixing said signals of frequency f_a and f_c with said signal of frequency f_b to derive a mixed signal, means for amplitude detecting said mixed signal, and means responsive to said amplitude detected mixed signal for controlling the frequency f_b of said signal from said controllable oscillator to be

$$\frac{f_a + f_c}{2}$$

3. In combination, a source of a signal of highly stabilized frequency f , means responsive to said signal of frequency f for providing at least two signals f_a and f_c of substantially the same high stability but of different frequency, a controllable source of a signal of frequency f_b , means for multiplying said signals of frequency f_a and f_c with said signal of frequency f_b to derive a first resultant signal of frequency dependent upon the products $f_b - f_a$ and $f_c - f_b$, means for amplitude detecting said first resultant signal, and means responsive to said amplitude detected resultant signal for controlling the frequency f_b of signals from said controllable oscillator to be

$$\frac{f_a + f_c}{2}$$

a source of a second controllable signal of frequency f_d , means for multiplying said signal of frequency f_a with said signal of frequency f_b to derive a second resultant signal, a controllable source of signal of frequency f_e , means responsive to the relative phase of said signal of frequency f_e and said second resultant signal for providing a third resultant signal, and means responsive to said third resultant signal for controlling the frequency f_d of said signal from said second controllable source to be $f_b \pm f_e$.

4. In combination, a source of a signal of highly stabilized frequency f , means for providing at least two harmonically related signals f_a and f_c in response to said signal of frequency f , a first controllable source of a signal of frequency f_b , means for mixing said signals of frequency f_a and f_c with said signal of frequency f_b to derive a first mixed signal, means for amplitude detecting said first mixed signal, means responsive to said amplitude detected first mixed signal for controlling the frequency f_b of signals from said controllable oscillator to be

$$\frac{f_a + f_c}{2}$$

a source of a second controllable signal of frequency f_d , means for mixing said signal of frequency f_d with said signal of frequency f_b to derive a second mixed signal, a controllable source of signal of frequency f_e , means responsive to said signal of frequency f_e and said second mixed signal for providing a resultant signal having an amplitude and a polarity which is a function of the relative phases of said second mixed signal and said signal of frequency f_e , and means responsive to said resultant signal for controlling the frequency f_d of said signal from said second controllable source to be $f_b \pm f_e$.

5. In combination, a source of a signal of highly stabilized frequency f , means responsive to said signal of frequency f for providing at least two signals of frequency f_a and f_c respectively, a controllable source of a signal of frequency f_b , means responsive to the relative frequency of said signals of frequency f_a , f_b and f_c to derive a first resultant signal, means responsive to said first resultant signal for controlling the frequency f_b of said signal from said controllable oscillator to be

$$\frac{f_a + f_c}{2}$$

a source of a second controllable signal of frequency f_d , means responsive to the relative frequency of said signal frequency f_d and said signal of frequency f_b to derive a second resultant signal, a controllable source of signal of frequency f_e , means responsive to the relative phase of said signal of frequency f_e and said second resultant signal for providing a third resultant signal, and means responsive to said third resultant signal for controlling the frequency f_d of said signal from said second controllable source to be $f_b \pm f_e$.

6. In combination, first means comprising a source of a signal of highly stabilized frequency f , means for deriving from said signal of frequency f at least two signals f_a and f_c of substantially the same high frequency stability, a controllable source of a signal of frequency f_b , means for multiplying said signals of frequency f_a and f_c with said signal of frequency f_b to derive a multiplied signal, means responsive to said multiplied signal for maintaining the frequency f_b of signals from said controllable source equal to

$$\frac{f_a + f_c}{2}$$

at least one second means comprising a second controllable source of signals of frequency f_d and f_e , means for multiplying said signals of frequency f_b , f_d and f_e to derive a second multiplied signal, and means responsive to said second multiplied signal for maintaining the frequency f_e of signals from said second source equal to the difference between the frequencies of signals of frequency f_b and f_d .

7. In combination, a source of a first and second signal of frequency f_a and f_c respectively, means for deriving a third signal of frequency f_b from said first and second signal wherein

$$f_b = \frac{f_a + f_c}{2}$$

a fourth signal of frequency f_e , means for deriving a fifth signal of frequency f_d from said fourth and third signals wherein the frequency f_e equals the difference between the frequencies f_b and f_d .

8. In combination, a source of a signal of highly stabilized frequency f , means for deriving from said signal at least two signals f_a and f_c of substantially the same high frequency stability, a source of a signal of frequency f_b , means for multiplying said signals of frequency f_a and f_c with said signal of frequency f_b to derive a multiplied signal, and means responsive to said amplitude detected multiplied signal for maintaining the frequency f_b of signals from said controllable oscillator equal to

$$\frac{f_a + f_c}{2}$$

9. In combination, a source of a first, a second and a third signal of frequency f_a , f_b and f_c respectively, means responsive to the relative frequencies of said first, second and third signals for deriving a control signal, and means responsive to said control signal for maintaining the frequency f_b of said source equal to

$$\frac{f_a + f_c}{2}$$

10. In combination, a source of a first, a second and a third signal of frequency f_a , f_b and f_c respectively, means responsive to the relative frequencies of said first, second and third signals for deriving a control signal, and means responsive to said control signal for maintaining the frequency f_b of said source equal to

$$\frac{f_a + f_c}{2}$$

a source of a fourth and fifth signal of frequency f_d and f_e respectively, means responsive to the relative

7 frequencies of said second, fourth and fifth signals for deriving a further control signal, and means responsive to said further control signal for maintaining the frequency f_d of said last-named source at a value such that the frequency f_e is the difference frequency between said fourth and second signals.
